UNITED STATES PATENT OFFICE.

JOHN S. LACEY, OF COLUMBUS, OHIO.

TEMPORARY BINDER.

Application filed February 13, 1924. Serial No. 692,608.

This invention relates to record leaf binders and more particularly to a temporary binder as distinguished from the ordinary loose-leaf binder or distributor. In the offices of registers of wills, recorders of deeds, etc., it is customary to employ loose-leaf binders of the well known types which are now upon the market. From such a binder, a clerk will extract a leaf, make a record thereon, and replace the leaf. To accomplish this the binder must be unlocked, the various leaves more or less disturbed in order to remove the leaf required for use, and the binder relocked after removal of the leaf, unless, through carelessness, it is permitted to remain unlocked, in which event further disturbance or disarrangement of the leaves is liable to occur. After the record has been made upon the leaf, the clerk is required to again unlock the binder, replace the leaf in its proper place among the leaves already present, and then relock the binder. All of this consumes considerable time and the task must be performed with more or less care and skill. The present invention, therefore, has as its primary object to provide a temporary binder into which may be placed the leaves which are contained within a loose leaf binder of ordinary construction, the binder embodying the invention being so constructed that by an extremely simple manipulation of its parts, its leaf binding members may be relatively separated so as to permit of the removal of a blank leaf from the front of the binder and the placement of a completed record leaf in the back of the binder, this operation being repeated as successive leaves are written so that when the entire number of leaves have been written upon, the assemblage may be replaced in the original binder and a permanent record thus obtained. Therefore, the present invention contemplates something which is entirely separate and distinct from any loose-leaf binder which has heretofore been devised or is upon the market and in use, and likewise distinguishes from a distributor, inasmuch as in each instance considerable time and labor is required in manipulating such devices, whereas in the present instance the device serves merely as a temporary binder or, in other words, as a storing means for taking care of record leaves as they are being prepared by the clerk. Thus, in itself, the device is not a binder in the ordinarily ac-

cepted meaning of the term, but is more properly deemed an intermediary by means of which the proper care may be taken of record leaves as they are written upon and until a volume of such leaves has been accumulated.

Another object of the invention is to provide a temporary binder in the manipulation or operation of which no especial care on the part of a clerk is required in the removal and replacement of the record leaves, as in the use of the permanent type of loose-leaf binders now on the market, the device of the present invention being, as previously stated, entirely distinct from such devices in that in the use of the present device the leaves are removed, assembled, from an ordinary binder, placed in the device of the invention, and records made upon respective leaves as they are removed from and afterwards replaced in the device. Therefore, the present invention contemplates so constructing one of the cover members of the device that in replacing leaves, after records have been written thereon, it will be only necessary for the clerk to slip the leaf into place, without any particular attention as to adjustment of the leaf, and then close or lock the binder, thereby saving time which has heretofore been consumed in adjusting such leaves.

Another object of the invention is to provide a temporary binder embodying means for guiding the leaves into proper position when they are reinserted into the binder after records have been written thereon, which means may be adjusted to accommodate leaves which have been trimmed to different sizes. In other words, a printed record leaf is trimmed after printing, in accordance with the position of the impression upon the leaf and for this reason it frequently happens that there will be a considerable variation in the dimensions of record leaves of different kinds, and through the instrumentalities of the present invention, such leaves, regardless of their dimensions, may be properly positioned automatically and without any particular attention on the part of the clerk.

A further object of the invention is to provide, in a temporary binder of the class described, means whereby the cover members of the binder may be held in their closed position so as to maintain the assemblage of leaves in the proper position and prevent

them from becoming rumpled or disarranged.

Another object of the invention is to provide a temporary binder for record leaves which will accommodate leaves from any of the ordinary loose-leaf binders now on the market, so that a temporary binder of standard size, embodying the principles of the present invention, may be placed upon the market and employed successfully regardless of the particular type of loose-leaf binders in which the permanent records are to be contained, and likewise regardless of the size of the leaves.

15 A further object of the invention is to so construct the binder that when it is locked, there will be no likelihood of a disarrangement of the component elements of the locking device which would permit separation 20 of the cover members of the binder and a disarrangement of the leaves bound therebetween.

In the accompanying drawings:

25 Figure 1 is a perspective view of a temporary binder embodying the present invention;

30 Figure 2 is a vertical transverse sectional view taken substantially on the line 2—2 of Figure 1 looking in the direction indicated by the arrows;

35 Figure 3 is a vertical longitudinal sectional view taken substantially on the line 3—3 of Figure 2 looking in the direction indicated by the arrows;

40 Figure 4 is a vertical transverse sectional view in detail taken substantially on the line 4—4 of Figure 1 looking in the direction indicated by the arrows;

45 Figure 5 is a similar view on the line 5—5 of Figure 3;

50 Figure 6 is a detail sectional view of one end of the binder, as shown in Figure 3, illustrating more particularly the locking mechanism of the binder;

55 Figure 7 is a bottom plan view, with the bottom plate removed, illustrating a modification of the locking means;

60 Figure 8 is a detail longitudinal sectional view taken substantially on the line 8—8 of Figure 7 and illustrating the means for holding the shifting bar of the locking mechanism in set position.

65 The binder embodying the present invention includes a back which is indicated in general by the numeral 1 and which may be of the construction illustrated in the drawings or of any other desired construction. As illustrated, the said back comprises a hollow body member which is preferably formed of sheet metal and comprises a top 2 and sides 3, the member being closed at its rear and front ends respectively by walls 4 and 5. The bottom of the body member is closed by a plate 6 which may be removably secured to the said end walls 4 and 5 as illus-

trated in Figure 3, and likewise the top and sides 2 and 3 of the body member of the back may be secured to the said end walls 4 and 5 so that a hollow substantially rectangular body is provided to support the cover members and the parts associated therewith and to house the locking and separating devices for the said cover members as will presently be more specifically described. In practice, the construction of the back 1 may be modified, of course, in various ways so that what is shown in the drawings is to be taken merely as illustrative of one embodiment of the invention, so far as this feature is concerned. In the form of the invention shown in Figures 1 to 6, inclusive, the top 2 of the back is provided at its longitudinal central portion with a transversely concave rest portion 7 upon which the inner edges of the record leaves are to be disposed in the same manner in which they are arranged in the original binder, it being understood that these record leaves are to be removed, in their assembled relation, from the original binder as purchased on the market and then placed within the temporary binder embodying the invention. These leaves are indicated in the drawings by the numeral 8 and the leaves are held in their assembled relation by the usual posts which are indicated by the numeral 9 and which are curved to correspond substantially to the curvature of the concave rest portion 7 of the top 2, the posts fitting through the usual slots or openings 10 which are present in the leaves of the original binder. It will be understood, therefore, that the rest portion 7 is of a width corresponding substantially to the thickness of the assemblage of leaves as taken from the ordinary binder and it will presently be made apparent that when the leaves are placed in their assembled relation with their rear edges resting upon the depressed rest portion 7, and the covers of the binder are closed, they will be held in substantially the same manner as when permanently bound.

70 The cover members of the binder are indicated in general by the numeral 11 and each member is preferably formed of sheet metal and the members are of counter-part construction. Each of the cover members is of substantially rectangular form and of slightly greater marginal dimensions than the maximum marginal dimensions of the leaves to be disposed within the binder. Each cover member is provided at its lower edge with a longitudinally extending hinge member 12 which is likewise preferably formed of sheet metal and so formed as to accommodate a pintle rod 13 which extends through a cylindrical portion 14 of the said member. Cover supporting members 15 are associated with the back 1 and each of these cover supporting members comprises a 75

folded sheet metal base 16, the under ply of which is disposed upon the upper side of the top 2 of the base or back 1, the upper ply of each member resting flat upon the under ply and being provided, along one longitudinal margin, with an upstanding flange 17, the upper portion of which is turned substantially horizontally as at 18 so as to provide a longitudinal groove 19 the open side of which is presented toward the leaves when they are disposed within the binder. At suitable intervals, the lower ply of the base 15 is provided with upstanding pintle lugs or ears 20 which extend 15 across the open side of the groove 19, but which are so arranged with relation to each other that any ordinary binder leaves and their posts 19 may be accommodated within the binder. In other words, these 20 posts, in various makes of binders, are spaced various distances apart and their arrangement may somewhat vary, but by a selected arrangement of the pintle members 20, the intervening uncovered portions of 25 the groove 19 in the cover supporting members 15 are permitted to accommodate the posts of binders of all makes. The pintle members 20 of course engage the pintle rod 13 so that the cover members 11 are connected with the cover supporting members 15 for swinging movement so that the binder may be opened or closed as occasion 30 may require. As before stated, the cover supporting members 15 are disposed upon 35 the upper side of the top 2 of the back 1, and in order to provide for relative displacement of the said cover supporting members with relation to each other and with relation to the seating portion 7 of the 40 said top of the back, various means may be employed. In Figures 1 to 6, inclusive, the adjusting means comprises companion rack bars 21 and 22 and these bars are provided with upturned right-angularly extending 45 ends 23 which are reduced in diameter and threaded as indicated by the numeral 24 and which have their threaded reduced portions fitted through slots 25 which are formed in the said top 2 of the back 1, the 50 slots extending transversely in parallelism and adjacent the upper and lower ends of the said back. In reducing the upturned ends 23 of the rack bars 21, shoulders 25 are provided, and a washer 26 is fitted onto 55 the reduced portion of each of these rack bar ends and engages the underside of the top 2 of the back 1. The said reduced portions 24 of the rack bar ends are fitted through openings 27 provided in the faces 60 of the cover supporting members 15, and a nut 28 is threaded onto each of the said reduced portions 24 and may be adjusted to vary the tension of a spring 29 which is likewise arranged upon the said reduced 65 portions and confined between the nut and the upper side of the respective cover supporting member 15. It will now be evident that by adjusting the nut 28, the tension of the spring 29 may be varied so that the cover supporting members 15 may be slidably and yet firmly held in position against the upper side of the top 2 of the back. The rack bars 21 and 22 have their toothed sides presented in confronting relationship to each other and pinions 30 coat with the 70 said bars and are fixed upon a shaft 31 which is suitably journaled in brackets 32 secured upon the under side of the rest portion 7 of the said top 2 of the back. The shaft 31 extends longitudinally of the back 80 of the device and one end of the shaft is presented opposite an opening 33 which is formed in the end 5 of the said back, this end of the shaft being squared, as indicated by the numeral 34, so as to adapt it for the 85 application thereto of an operating crank 35 which comprises a shank 36 having a head 37 at one end formed with a socket 38 to accommodate the squared end of the shaft 31, whereby the crank handle may be 90 manipulated so as to impart rotary motion to the shaft and thus relatively shift the rack bars 21 and 22 and correspondingly adjust the cover supporting members 13. A pinion 39 is fixed upon the shaft 31 inwardly of its squared end 34 and a detent 40 comprising a leaf spring 41 is employed in connection with the pinion and has a tooth portion 42 which is adapted to seat 95 between the teeth of the pinion 39, the said leaf spring being secured at its opposite end, to the under side of the top 2 of the back 1. Due to the resiliency of the leaf spring 41, its tooth portion 42 is normally held in engagement with the teeth of the pinion 39, and due to such engagement of the parts the shaft 31 is normally held against rotation so that when the binder is closed or locked, there is no liability of separation of the cover supporting members 100 and the covers carried thereby and consequently no liability of disarrangement or separation of the leaves which are held within the binder. However, when it becomes necessary to remove a leaf from the 105 binder or place a record bearing leaf therein, it is required that the cover supporting members be relatively separated or moved apart through rotation of the shaft 31 and a shifting of the rack bars 21 and 22. In 110 order that this may be effected and the detent 40 rendered temporarily inactive while the shaft 31 is being rotated, the head 37 of the operating crank 35 is tapered in the direction of its forward end and the end of the leaf spring 41 which carries the tooth member 42 is provided with an inclined or cam edge 43 which is positioned in the path of the head 37 as the head of the crank is 115 fitted onto the squared end of the shaft. 120

125

130

By reference to Figures 3 and 6 of the drawings it will be evident that when the crank member is inserted through the opening 33 and its head 37 is slipped onto the end 5 of the shaft 31, the conical surface of the head will ride beneath the edge 43 of the leaf spring detent 41 thereby elevating the tooth carrying end of the detent out of engagement with the pinion 39 and thereby 10 rendering the detent inactive so long as the said crank member is applied to the end of the shaft. Therefore, when the crank member is operated, the shaft may be freely rotated so as to relatively adjust the rack 15 bars 21 and 22 and thereby correspondingly adjust the cover supporting members 15.

Inasmuch as a careless clerk might not properly position the crank handle and might endeavor to rotate the same without 20 the leaf spring detent 41 being rendered inactive through proper fitting of the head 37 to the squared end 34 of the shaft 31, and thereby cause damage to the elements of the operating device, a retaining device, 25 such, for example, as a wire spring 44 is employed and secured at one end, as at 45, to the inner side of the end wall 5 of the back 1 and is slidably engaged near its other end through an eye 46 upon the said 30 end wall of the back and extends approximately tangential to the opening 33 so that when the crank member 35 is inserted through the opening, the spring 44 will engage behind the inner end of the head 37 35 which end is rounded, as at 47, to provide a shoulder for this purpose, the engagement of the spring behind the shoulder serving to retain the crank member in proper engagement with the end of the shaft 31. Due 40 to the fact, however, that the shoulder is rounded, the crank member may be readily withdrawn after the binder has been closed.

From the foregoing description of this 45 form of the invention it will be evident that by applying the crank 35 and rotating the shaft 31 in one direction, the cover supporting members 15 may be relatively separated so as to permit of the introduction into the binder of the leaves from a loose-leaf record binder of any ordinary type, 50 the posts 9 remaining assembled with the leaves. After the leaves have been disposed in their assembled relation upon the concave rest portion 7 of the top of the back of 55 the device, the shaft 31 may then be rotated in the opposite direction so as to shift the cover supporting members toward each other thereby bringing them substantially to the 60 position shown in Figure 5 of the drawings in which position the inner marginal portions of the leaves will be clamped and firmly bound between the adjacent sides of the 65 said cover supporting members with the ends of the posts 9 projecting into the channels 19 of the said cover supporting members.

When the cover supporting members are relatively separated as illustrated in Figure 2 of the drawings, the ends of the posts 9 will be clear of the channels and it is while the members are in this position of adjustment that the leaves may be removed and replaced. In practice, the clerk will manipulate the binder so as to effect the adjustment shown in Figure 2 and will remove the first leaf at the left hand side of the stack of 70 leaves, and, if no record leaf has in the meantime been prepared, will again close the binder. After the clerk has written or typed the removed sheet, he or she will again open the binder in the manner illustrated in the 80 said Figure 2 and will insert the sheet in position at the right hand side of the bank or stack of leaves. In order that all necessity for accurately positioning the sheet at the time of its insertion may be obviated, 85 guides 48 are arranged at the opposite ends of the cover member at the right hand side of the binder. Each of these leaf guides comprises an attaching wing 49 and an outstanding right-angularly positioned guide 90 wing 50, the member being preferably formed from sheet metal. The cover 11 is formed with longitudinally extending parallel slots 51, and screws 52 are threaded through openings in the attaching wings 49 of the guides 48 and extend likewise through the slots 51 and are adapted to be tightened so as to secure the guides 48 in positions of 95 relative adjustment. It will be evident at this point that the guides may be so adjusted that their guiding wings 50 will be spaced apart a distance equal to the length of the leaves to be housed within the binder, 100 so that upon the introduction of any one leaf into the binder, the slots 10 in the leaf will 105 be in position to exactly register with the ends of the posts 9 and therefore when the binder is closed, the sheet will be automatically assembled with the ends of the said posts. This arrangement, therefore, provides for immediate and convenient placement of the leaves in the binder and, of 110 course, their removal therefrom can be equally as readily and expeditiously effected. At this point it is to be observed that the device embodying the invention is a temporary 115 binder as distinguished from a permanent loose-leaf record binder or a distributor. In other words, the device is to be employed in connection with the ordinary loose-leaf record binders, the leaves in their assembled 120 relation being removed from the ordinary loose-leaf record binder and the cover of the binder, or, in other words, the binder itself being laid aside for the time being. The 125 leaves in blank form are then removed from the temporary binder one at a time and records typed or written thereon, they being replaced in the binder at the right hand side thereof as they are completed. After the 130

entire number of leaves has been typed or written upon, the assemblage is then removed from the temporary binder and placed in the original binder or cover and 5 permanently locked in place so that the assemblage then constitutes a permanent record.

In order that the covers 11 of the binder may be held relatively closed when the 10 binder is not in use and likewise in order that these covers may be swung to open position to gain access to the completed or typed leaves of the binder while the same is still in its incomplete form, means is provided 15 which will now be described.

The means referred to above comprises latch levers 53 which are mounted one upon each of the covers 11 by means of a pivot 54, and the lower end portion of each latch 20 member is deflected laterally and extended along a curved line as indicated by the numeral 55, the lower extremity of the lever being bent to provide a hook 56 designed to engage over the outer longitudinal edge of 25 the face of the respective cover supporting member 15 as best shown in Figure 2 of the drawings. A leaf spring 57 is secured to the side of the lever 53 which is presented toward the cover 11 and the spring at its 30 free end portion engages against the said cover thereby holding the lever in position for the engagement of its hooked end 56 with the said cover supporting member. It is preferable that each lever be provided with 35 an abutment stud 58 for engagement against the cover 11 to limit the swinging movement of the lever under the influence of the spring 57, it being observed that the spring 57 is located above the pivot 54 and that the stop 40 lug 58 is located below the said pivot. The lower end of each lever engages in a slot 59 formed in the top 2 of the back 1 of the binder and by reference to Figure 2 and more particularly to the full line illustration 45 therein, it will be observed that when the cover members 11 are closed, the hooked ends 56 of the levers 53 will automatically engage with the faces of the cover supporting members and thus lock the said covers 11 in their 50 closed position. When it is desired to gain access to the leaves, for the mere purpose of reference to records contained thereon, the levers 53 may be manipulated so as to disengage their hooked ends from the bases 55 of the cover supporting members and the covers may then be swung to open position as illustrated in dotted lines in the said Figure 2, the arcuate lower end portions 55 of the levers working through the slots 59 and 60 extending into the interior of the back 1.

In the form of the invention shown in Figures 7 and 8 of the drawings, the back of the binder is indicated in general by the numeral 60 and the back is provided with 65 slots 61, in its top, corresponding to the slots

25 of the previously described form. In this embodiment of the invention the cover supporting members are indicated by the numeral 62 and they are riveted, through the slots 61, to parallel adjusting bars 63 disposed against the under side of the top of the back, the said bars 63 being carried by and having connection with the cover supporting members in the manner stated. The numeral 64 indicates levers which are pivotally mounted at a point midway between their ends to the under side of the top of the back of the device as indicated by the numeral 65. One end of each of the levers 64 is connected to a collar which is indicated in the drawings by the numeral 56 and is freely slideable on the respective rod or bar 63. To the opposite ends of the levers 64 there are connected links 67 which links are in turn pivotally connected to a slidably 75 mounted actuating bar 68 supported in a guide 70 and likewise in an opening 71 in the end wall of the back of the binder. The bar 68 carries upon its under side near its outer end, a shoulder 69, and a leaf spring 90 72 is secured to the said end wall of the back and bears upon the handle end 73 of the said bar 68 to hold the bar depressed and with the shoulder 69 engaged behind the said wall at the lower side of the said opening 71. The parts, when in this position, will appear as in Figures 7 and 8. When it is desired to relatively separate the cover-holding members, the handle end of the bar 68 is slightly elevated and the bar is pulled 100 outwardly thereby effecting a rocking movement of the levers 64 and a relative separation of the bars 63 and the respective cover supporting members.

Having thus described the invention, what is claimed as new is:

1. A temporary binder for an assemblage of record leaves which have been removed, with their supporting posts, from a loose-leaf binder, comprising relatively separable 110 cover-supporting members, having opposed channeled sides to freely accommodate the ends of the said posts, covers supported thereby, and means operable to relatively adjust the said members to position clamping 115 the assemblage and to position spaced from the opposite sides of the assemblage and clearing the ends of the posts, whereby, in the latter instance, to permit of removal of a blank leaf from one side of the assemblage and the placement of a written leaf 120 at the other side of the assemblage.

2. A temporary binder for an assemblage of record leaves which have been removed, with their supporting posts, from a loose-leaf binder, comprising relatively separable 125 cover-supporting members having opposed open channeled sides to freely accommodate the ends of the said posts, covers supported thereby, means operable to relatively adjust 130

the said members to position clamping the assemblage and to position spaced from the opposite sides of the assemblage and clearing the ends of the posts, whereby, in the latter 5 instance, to permit of removal of a blank leaf from one side of the assemblage and the placement of a written leaf at the other side of the assemblage, and means associated with the cover at the said other side of the assemblage for guiding into position the inserted leaf when the cover supporting members are again adjusted to clamp the assemblage of leaves.

3. A temporary binder for an assemblage 15 of record leaves which have been removed, with their supporting posts, from a loose-leaf binder, comprising relatively separable cover-supporting members having opposed open channeled sides to freely accommodate 20 the ends of the posts, covers supported by said members, and means operable to relatively adjust the said members to position clamping the assemblage and to position spaced from the opposite sides of the assemblage and clearing the ends of the posts, whereby, in the latter instance, to permit of removal of a blank leaf from one side of the assemblage and the placement of a written leaf upon the said posts at the other side 25 of the assemblage.

4. A temporary binder for an assemblage 30 of record leaves which have been removed, with their supporting posts, from a loose-leaf binder and which leaves are provided with the usual openings to receive said posts, comprising relatively separable cover-supporting members having opposed open channeled sides to freely accommodate the ends 35 of the posts, covers supported by said members, means operable to relatively adjust the said members to position clamping the assemblage and to position spaced from the opposite sides of the assemblage and with the open sides of the said clamping members 40 clear of the ends of the posts, whereby, in the latter instance, to permit of removal of a blank leaf from one side of the assemblage and the placement of a written leaf upon the said posts at the other side of the assemblage, 45 and means associated with the cover at the said other side of the assemblage for guiding into position the inserted leaf to locate the openings therein opposite the posts and effect engagement of the ends of the posts in the said openings when the said cover-supporting members are adjusted to clamping 50 position.

5. A temporary binder for an assemblage 55 of record leaves which have been removed, with their supporting posts, from a loose-leaf binder, comprising relatively separable cover-supporting members having opposed open channeled sides to freely accommodate the ends of the said posts, covers supported 60 thereby, means operable to relatively adjust

the said members to position clamping the assemblage and to position spaced from the opposite sides of the assemblage whereby, in the latter instance, to permit of removal of a blank leaf from one side of the assemblage 70 and the placement of a written leaf at the other side of the assemblage, and guides adjustably mounted upon the cover at the said other side of the assemblage and constituting means for guiding into proper position with 75 relation to the post ends, the leaf last-mentioned, whereby, when the cover-supporting members are adjusted to clamping position, the inserted leaf will be suitably engaged with said supporting posts.

6. A temporary binder for an assemblage 80 of record leaves which have been removed, with their supporting posts, from a loose-leaf binder, comprising a base, cover-supporting members slidably adjustable upon 85 the said base toward and from each other, covers hingedly connected with the said cover-supporting members, means operable to relatively adjust the said members to position clamping the assemblage and to position spaced from the opposite sides of the assemblage, whereby, in the latter instance, to permit of removal of a blank leaf from one side of the assemblage and the placement of a written leaf at the other side of 90 the assemblage, and means for maintaining the said covers in an upright substantially parallel position independent of the adjustment of the said cover-supporting members, the means comprising locking levers mounted 95 upon the outer sides of the covers and having engaging hook portions for coaction with the respective cover-supporting members.

7. A temporary binder for an assemblage 100 of record leaves which have been removed, with their supporting posts, from a loose-leaf binder, comprising a base, cover-supporting members slidably adjustable upon 105 the said base toward and from each other, covers hingedly connected with the said cover-supporting members, means operable to relatively adjust the members to position clamping the assemblage and to position spaced from the opposite sides of the assemblage, whereby, in the latter instance, to permit of removal of a blank leaf from one side of the assemblage and the placement of a written leaf at the other side of the assemblage, and means for maintaining the said 110 covers in an upright substantially parallel position independent of the adjustment of the said cover-supporting members, the means comprising locking levers mounted upon the outer sides of the covers and having engaging hook portions for coaction with the respective cover-supporting members, the said base being hollow and having 115 slots in its upper side to permit of entrance of the locking portions of the said locking 120 levers.

levers into the said base upon swinging of the covers to open position.

8. A temporary binder for an assemblage of record leaves removed from a loose-leaf binder, comprising a supporting base of hollow construction, cover-supporting members mounted upon the said base and adjustable toward and from each other, covers supported by the said members, and means operable to adjust the said members comprising rack bars connected with the members and extending in parallelism within the said base, a shaft rotatably mounted within the base, means for rotating the shaft, a pinion upon the shaft meshing with the said rack bars, a second pinion fixed upon the shaft, and a detent having a tooth portion for coaction with the latter pinion and provided with a cam portion, the means for rotating the said shaft comprising an operating crank having a head to fit the end of the shaft, the said head being exteriorly of tapered form for coaction with the cam portion of the detent to disengage the toothed portion of the detent from the said latter pinion when the said head of the crank handle is fitted to the said end of the shaft, and means for coaction with the head of the crank handle to restrain the handle against accidental displacement with relation to the end of the shaft when the said crank handle has assumed a position in which the head is rendered inactive.

10. A temporary binder for an assemblage of record leaves which have been removed, with their supporting posts, from a loose leaf binder, comprising a base having a supporting portion for the said assemblage of record leaves, relatively separable cover supporting members mounted upon the base and having opposed channeled sides to freely accommodate the ends of the said posts, the said cover supporting members being mounted upon the base at opposite sides of the said supporting portion thereof, covers supported by the said cover supporting members, and means operable to relatively adjust the said members upon the base in position clamping the assemblage of leaves and to position spaced from the opposite sides of the assemblage and clearing the ends of the posts, whereby, in the latter instance, to permit of removal of a blank leaf from one side of the assemblage and the placement of a written leaf at the other side of the assemblage.

9. A temporary binder for an assemblage of record leaves removed from a loose-leaf binder, comprising a supporting base of hollow construction, cover-supporting members mounted upon the said base and adjustable toward and from each other, covers supported by the said members, and means operable to adjust the said members comprising rack bars connected with the members and extending in parallelism within the said base, a shaft rotatably mounted within the base, means for rotating the shaft, a pinion upon the shaft meshing with the said rack bars, a second pinion fixed upon the shaft, a detent having a tooth portion for

In testimony whereof I affix my signature.

JOHN S. LACEY. [L.S.]
